UNITED STATES PATENT OFFICE.

ADELBERT S. NICHOLS, OF NEW YORK, N. Y.

DESIGN FOR A MANTEL.

SPECIFICATION forming part of Design No. 30,402, dated March 28, 1899.

Application filed February 23, 1899. Serial No. 706,586. Term of patent 7 years.

To all whom it may concern:

Be it known that I, ADELBERT S. NICHOLS, a citizen of the United States, residing in the city and State of New York, have invented 5 and produced a new and original Design for a Mantel, of which the following is a specification.

In the drawings, Figure 1 is a front elevation, and Fig. 2 is a side elevation, of the present design.

The leading feature of this design relates to the side panels A and B, projecting shelves C and D, the supporting-columns E, the shelf F, the projecting case G between the panels A

and B, and an ornamental head H, substantially as represented.

Having described my invention, what I claim as new, and desire to secure by Letters Patent, is—

The design for a mantel, substantially as described and represented.

Signed by me this 20th day of February, 1899.

ADELBERT S. NICHOLS.
